UNITED STATES PATENT OFFICE

EDWARD E. EKVALL, OF ELGIN, ILLINOIS, ASSIGNOR TO THE W. H. HOWELL COMPANY,
OF GENEVA, ILLINOIS, A CORPORATION OF ILLINOIS

DESIGN FOR A SMOKING STAND

Application filed August 21, 1929. Serial No. 32,480. Term of patent 3½ years.

To all whom it may concern:

Be it known that I, EDWARD E. EKVALL, a citizen of the United States, residing at Elgin, in the county of Kane and State of Illinois, have invented a new, original, and ornamental Design for Smoking Stands, of which the following is a specification, reference being had to the accompanying drawing, forming part thereof.

The figure is a perspective view of a smoking stand showing my new design.

I claim:

The ornamental design for a smoking stand, as shown.

EDWARD E. EKVALL.
